REFUSE RECEPTACLE HOLDER

Earl F. Bennett and Otto Jarvis, Houston, Tex.

Application March 19, 1952, Serial No. 277,511

2 Claims. (Cl. 248—147)

1

This invention relates to a novel mobile holder or stand for refuse receptacles such as garbage cans and trash cans and is primarily adapted as a stand and holder for garbage cans.

Among the primary objects of the present invention is to provide a stand by means of which the lid may be maintained at all times on the open top of the receptacle and is nondetachably supported by the stand to prevent loss of the lid when the receptacle is removed from the stand by garbage and trash collectors for emptying.

Another object of the invention is to provide a stand which will support the receptacle off the ground in a sanitary manner with the bottom of the receptacle exposed to air to thus prevent rusting, corrosion or contamination.

Another object of the invention is to provide a stand which will readily maintain itself in any position in which it is placed but which may be tilted to provide a wheeled support to enable the stand and a filled receptacle to be readily rolled to a position to be emptied by a garbage or trash collector.

Another object of the invention is to provide a novel foot actuated means for lifting the lid to expose the open top of the receptacle to facilitate the emptying of garbage or trash therein and which automatically returns the lid to a position for closing the top of the receptacle.

Another object of the invention is to provide a stand from which the receptacle can be readily removed and replaced without damage thereto and having means for latching the lid in a raised position while the receptacle is removed for emptying.

Another particularly important object of the invention is to provide a novel linkage connection between the lid and foot actuated lid lifting means whereby binding of the lid with the top of the receptacle is prevented when the lid is moved upwardly out of engagement with the receptacle and which will eliminate the difficulties frequently encountered in removing a lid from a trash or garbage can.

Various other objects and advantages of the invention will hereinafter become more fully apparent from the following description of the drawings, illustrating a presently preferred embodiment thereof, and wherein:

Figure 1 is a front elevational view of the stand with the receptacle applied thereto;

Figure 2 is a vertical sectional view thereof taken substantially along a plane as indicated by the line 2—2 of Figure 1;

Figure 3 is a horizontal sectional view of the

2

stand taken substantially along a plane as indicated by the line 3—3 of Figure 2;

Figure 4 is a bottom plan view thereof;

Figure 5 is a fragmentary vertical sectional view similar to Figure 2 but showing the lid in its initial movement upwardly and out of engagement with the receptacle;

Figure 6 is an enlarged fragmentary vertical sectional view taken substantially along a plane as indicated by the line 6—6 of Figure 2, and

Figure 7 is a fragmentary horizontal sectional view taken substantially along a plane as indicated by the line 7—7 of Figure 1 showing the foot actuated lever in a latched position.

15 Referring more specifically to the drawings, the receptacle supporting stand in its entirety is designated generally 10 and includes a pair of corresponding spaced upright rear frame members, each designated generally 11, which are of

20 angular cross section and each of which includes a front side 12 and a rearwardly extending side 13. The sides 12 are disposed coplanar and the sides 13 are disposed parallel and extend rearwardly from the outer edges of the sides 12. A

25 pin or rod 14 extends between and through the upper ends of the sides 13 and is secured thereto. A sleeve 15 is mounted on the rod 14 between the sides 13 and combines therewith to form a handgrip. The upper ends of the front sides 12 terminate below the handgrip 14, 15 and are preferably bent inwardly as seen at 16, adjacent their upper ends. A spacing member 17 of angular cross section extends between and is secured at its ends to the inner sides of the frame mem-

30 bers 11, adjacent the lower ends thereof and combines with the sleeve 15 to rigidly maintain the frame members 11 in spaced substantially parallel relationship to one another. An axle 18 extends through the frame sides 13 adjacent to the spacing member 17 and projects outwardly from said sides 13. A wheel 19 is mounted on each end of the axle 18. The wheels 19 may be equipped with rubber tires and may be journaled on the ends of the axle 18, or the axle

35 may be journaled in the frame sides 13 and secured to the wheels 19.

40 A substantially U-shaped receptacle supporting member 20 is secured to and supported on the front sides of the frame sides 12, near their lower ends. The receptacle supporting member 20 is of angular cross section and includes a horizontal bottom portion 21 and an upstanding outer wall 22 which rises from the outer edge of the bottom portion 21. The substantially U-shaped member 20 has a substantially straight inter-

mediate portion, as illustrated in Figure 3, and a part of the wall 22 of said intermediate portion is disposed against the front face of the frame sides 12 and secured thereto in any suitable manner as by means of the fastenings 23. As seen in Figures 3 and 4, the ends or legs of the receptacle supporting member 20 extend forwardly from the frame members 11 in diverging relationship to one another. Said legs of the member 20 are connected near to but spaced from their ends by a brace 24, the ends of which are secured by fastenings 25 to the undersides of complementary parts of the bottom portion 21. A pair of upright front leg members 26 are secured at their upper ends by fastenings 27, or in any other suitable manner to the outer face of the ends of the wall 22. The legs 26 extend downwardly from the ends of the receptacle supporting member 20 and have inturned lower ends 28 which rest on and are secured to the ends of a bar 29 which forms a foot member and which is disposed in substantially the same plane as the bottom portion of the wheels 19 and combines therewith to support the stand 10 in substantially an upright position, as illustrated in Figures 1 and 2. The inturned leg terminals 28 may be secured in any suitable manner as by additional fastenings 27 to the ends of the foot member 29.

A pair of spaced corresponding brace members 30 each includes an intermediate portion 31 which is disposed against and secured to the underside of the cross brace 24. Each brace 30 has a depending forward end 31 or 31a, each of which is provided with an outturned terminal 32 which is disposed on and secured to the foot member 29. Each brace 30 has a rearwardly and downwardly inclined rear portion 33 which terminates in a downturned terminal 34. The terminals 34 are secured to the front side of the spacing member 17. The braces 30 may be connected to the parts 17, 24 and 29 in any suitable manner as by means of fastenings 27.

A pair of apertured ears 35 are secured to and project forwardly from the brace portions 34 and are spaced from one another to loosely receive an end of a lever 36 therebetween. Said lever end is swingably connected to the ears 35 by a pivot pin 37 for vertical swinging movement. The lever 36 extends forwardly from the ears 35 through the space between the adjacent edges of the brace portions 31 and 31a which thus form a guide for the lever 36. A foot pedal or treadle 38 is secured to the forward end of the lever 36, forwardly of the brace portions 31 and 31a. A pair of spaced apertured ears 39 are secured to and extend rearwardly from the brace portions 31 and 31a, substantially above the lever 36 and accommodate therebetween the forward end of an upper lever 40. Said forward end of the lever 40 is swingably connected to the ears 39 by a bolt or pivot pin 41 which extends therethrough for swingably mounting the lever 40 for vertical swinging movement. The lever 40 extends rearwardly through the space between the brace portions 33 which form a guide for said lever and thence rearwardly through the space between the frame members 11. The levers 36 and 40 are connected to one another near their pivoted opposite ends by links 42 which are pivotally connected at their upper ends to the lever 40 and at their lower ends to the lever 36 by fastenings 43.

The rear end of the lever 40 is pivotally connected at 44 to the lower end of a connecting link 45 which is disposed behind the frame members 11 and extends upwardly from the lever 40. The

connecting link 45 is formed of upper and lower sections 46 and 46a, respectively, having overlapping adjacent ends provided with spaced openings 47 to receive fastenings 48 for connecting the sections 46 and 47 and to vary the length of the connecting link 45.

The front sides 12 of the frame members 11 are provided with vertically spaced openings 49 to selectively receive fastenings 50 for attaching a plate 51 to the rear surfaces of the sides 12 at different levels. The plate 51 is provided with a vertical upwardly opening slot 52 and with a pair of ears 53 which straddle said slot. A portion of a lever 54 extends loosely through the slot 52 and between the ears 53 and is swingably connected to the plate 51 by a pivot pin or fastening 55 which extends through the ears 53 and lever 54. The plate 51 thus forms an adjustably mounted pivot for the lever 54. The rear end of the lever 54 is connected by a fastening 56 to the upper end of the upper connecting link section 46 near the pivot 55. Said connecting link 45 is made extensible to accommodate the vertical adjustment of the plate 51 for receptacles of different heights, as will hereinafter become apparent. A lid 57 having a depending marginal flange 58 is provided with a pair of upstanding spaced ears 59 located near a portion of the periphery thereof and which accommodates therein a part of the lever 54 which is pivotally connected to the ears 59 by a pivot pin 60 at a point forwardly of but relatively near to the pivot pin 55. A second pair of ears 61 are fixed to and extend upwardly from the lid 57 in alignment with the ears 59 but more remote to the pivot 55. A pivot pin 62 extends between the ears 61 and loosely through an elongated slot 63 in the forward end of a link 64. The rear end of the link 64 is pivotally connected by a fastening 65 to the forward end of the lever 54 between the pivots 60 and 62.

As seen in Figure 1, the brace portion 31 near its lower end is provided with an inwardly opening downwardly inclined notch 66 disposed below the level of the forward end of the lever 36 when the lever 54 is in substantially a horizontal position, as illustrated in Figures 1 and 2.

A can or receptacle 67 having an open top is slidably and detachably supported on the bottom 21 of the support 20 and is held against rearward and lateral movement by the wall 22. However, the front of the support 20 is open to allow the can 67 to be slidably applied to or removed from said support 20 and the bottom of the support 20 is open forwardly of the cross brace 24 and between its forward terminals so that the can or receptacle 67 may be readily grasped on its underside for applying it to or removing it from the support 20. Thus, the application of the can to and its removal from the stand 10 is materially facilitated as the full can does not have to be initially lifted from the support 20 to be removed and may be slid horizontally back into position thereon. Consequently, the can will be subjected to much less damage as will the stand 10 in a normal use thereof so that the need for replacement of a damaged and battered can will be much less frequent than with other types of stands or holders now in use. It will also be apparent that the lid 57 when in engagement with the upper open end of the can 67 will retain the can or receptacle in a properly applied position. To elevate the lid 57 for the purpose of applying garbage or trash to the receptacle 67, the user merely

steps upon the treadle 38 to swing the lever 36 downwardly. This likewise causes the lever 40 to swing downwardly at its rear end due to the linkage connection 42 between the levers, thus exerting a downward pull on the connecting link 45. This causes the lever 54 to swing clockwise on its pivot 55, as seen in Figure 2 for elevating the forward part of the lever 54, disposed forwardly of the pivot 55. When this occurs, a very unique operation results. As the lever 54 initially swings upwardly from its position of Figure 2 to its position of Figure 5, the pivot 60 is elevated to initially elevate the portion of the lid 57 which is located near the pivot 55. This is accomplished without exerting a pull on the pivot 62 since the link 64 slides relatively to the pivot 62 due to the slot 63 therein provided for this purpose. Thereafter, when the parts are in their positions of Figure 5, a further clockwise swinging movement of the lever 54 exerts an upward pull on the pivot 62 for elevating and detaching the portion of the lid remote from the pivot 55 from the upper end of the can 67 and so that the lid may thereafter swing with the lever 54 upwardly to its dotted line position of Figure 5. In this position garbage or trash may be emptied into the receptacle 67, after which the pressure on the foot pedal 38 is released to allow the lever 54 to swing in the opposite direction under the weight of the lid 57 first back to its position of Figure 5 and then back to its position of Figure 2 to return the lid to a fully closed position. The weight of the lid 57 is also sufficient to swing the levers 36 and 40 upwardly and to elevate the connecting link 45, to return said parts to their positions of Figure 2. When the lid 57 is in its elevated, dotted line position of Figure 5, if it is desired to remove the can 67 for emptying the contents thereof, the forward end of the lever 36 is displaced to the right and into engagement with the notch 66, as illustrated in Figure 7, to thus latch the lever 36 in a depressed position to maintain the lid 57 in a fully opened position while the receptacle 67 is removed from the stand 10, emptied and replaced thereon. The lever 36 is then moved laterally in the opposite direction to disengage it from the notch 66 to allow the parts to return to their positions of Figure 2, as previously described. The lever 36 is of sufficient length and possesses sufficient resiliency to enable it to be displaced laterally into engagement with the notch 66.

It will be readily apparent that the foot member 29 will combine with the wheels 19 to normally support the stand 10 in an upright position and immovably. However, the user may grasp the handgrip 15 to rock the frame rearwardly on the axle 18 to thus elevate the bar or foot member 29. The stand 10 thus tilted and while supporting the filled receptacle 67 may be conveniently rolled on the wheels 19 from a position where the stand and receptacle are normally kept for use to a position from which the receptacle 67 will be emptied by a collector, thus relieving the user of the burden of actually lifting and carrying a filled receptacle or can to a collection point. It will also be readily apparent that the stand 10 will effectively prevent loss or damage to the lid 57 since the lid is not detached therefrom and is thus prevented from be-

ing lost or damaged. It will also be obvious that the stand 10 may be made in various sizes for accommodating receptacles of various cross sectional sizes in addition to the adjustable feature of each size for accommodating receptacles 67 of different heights.

Various modifications and changes are contemplated and may obviously be resorted to, without departing from the spirit or scope of the invention as hereinafter defined by the appended claims.

We claim as our invention:

1. In a stand of the character described adapted to support an open top receptacle detachably thereon, a lever pivotally connected to said stand for vertical swinging movement and having one end adapted to be disposed above the open top of the receptacle, a link pivotally connected at a rear end thereof to a forward end of said lever, a lid adapted to be normally supported on and closing the open top of the receptacle and disposed beneath said link and lever, means slidably and pivotally connecting the lid to the forward end of the link remote to the lever pivot, and means pivotally connecting the lid to the lever adjacent the lever pivot and between the lever pivot and the forward end of the lever whereby when the forward end of the lever is swung upwardly the lid portion disposed adjacent the lever pivot will be initially elevated relatively to the lid portion disposed remote to the lever pivot and while the link is sliding relatively to the lid, said first mentioned means thereafter in cooperation with the link and lever causing the lid portion disposed remote to the lever pivot to be swung upwardly.
2. In a stand of the character described adapted to support an open top receptacle detachably thereon, a lever pivotally connected near a rear end thereof to the stand for vertical swinging movement and having a forward end adapted to be disposed over the open top of the receptacle, a lid adapted to be normally supported on said closing the open top of the receptacle and disposed beneath the forward portion of the lever, a first means pivotally connecting the lid to the lever adjacent the lever pivot and between said pivot and the forward end of the lever, a link disposed above the lid having one end pivotally connected to the forward end of the lever and forming an extension thereof, and a second means pivotally and slidably connecting the other free end of the link to the lid remote to the lever pivot whereby when the forward end of the lever is swung upwardly the lid portion located adjacent the lever pivot will be initially elevated relatively to the lid portion disposed remote from said lever pivot after which said remote lid portion is elevated at an accelerated speed relatively to the lid portion located adjacent the lever pivot.

EARL F. BENNETT.
OTTO JARVIS.
